TOY GUN

Charles F. Lefever, Plymouth, Mich., assignor to
 Daisy Manufacturing Company, Plymouth,
 Mich., a corporation of Michigan

Application December 6, 1939, Serial No. 307,909

1 Claim. (Cl. 221—31.5)

In the general art of toy guns one type largely manufactured and used is characterized by the silent or substantially silent discharge of a projectile. Within this type is the class of so-called water pistols or guns which silently discharge liquid. Another type within the general art is commonly known as pop guns, these being adapted to produce a loud report without the discharge of any projectile. It is the primary object of the instant invention to combine in one structure a mechanism for the silent discharge of a projectile and associated means for substantially simultaneously producing a loud report. To this end the invention consists in the construction as herein-after set forth.

In the drawing:

Figure 1 is a central longitudinal section partly in elevation of my improved toy gun;

Figure 2 is a plan view thereof;

Figure 3 is a sectional end elevation;

Figure 4 is a side elevation.

My improved gun is preferably formed to simulate in appearance a double barreled gun or pistol. Thus as shown, the outer casing is formed of two pressed sheet metal sections A and A' each fashioned to have the double barreled portion A² and A³, the frame portion A⁴ and the handle portion A⁵. The two sections are secured together in the usual manner through the medium of cooperating struck out ears A⁶ which are clinched into engagement with each other. Within one of the barrels, shown as the upper barrel, is located a liquid discharge mechanism. This comprises a liquid holding cylinder B having a closure head B' at its outer end with a central small discharge aperture B² therein. A piston C is arranged within the cylinder to form a sealing engagement therewith, and a shank D connected to the piston extends rearward and out through an aperture in the rear wall of the casing being preferably provided at its rear end with a pull loop D'. The shank D is further provided with a series of ratchet teeth D² preferably on its upper side which are adapted to be successively engaged by a pawl E connected to a trigger F. The trigger is preferably formed of a sheet metal stamping U-shaped in cross section and bifurcated at its upper end to embrace the report producing mechanism hereinafter described.

The pop or report producing mechanism may be of any suitable construction and is preferably located in the other of the barrels. As shown, it comprises an air cylinder G fixedly secured within the lower barrel A³ by suitable means such as a struck-out ear G'. The forward end of this

cylinder is slightly contracted in diameter as indicated at G² to form a seat for a disk closure member H, which is normally held to its seat by a spring H' abutting at its forward end against struck-out ears H² integral with the casing. Within the barrel G is a piston I secured to a rearwardly extending shank I'. The shank has an upwardly offset portion I² which is enclosed within a guide member J of U-shaped cross section extending longitudinally of the casing and secured thereto at its rear end by a bent ear J'. The forward portion of the guide J is reduced in width to form a shoulder J² which together with a struck-out ear J³ forms an abutment for a spring K. The latter surrounds the forward portion J⁴ of the guide and extends beyond the same into the cylinder G bearing at its forward end against the piston I. The rear end of the offset portion I² of the shank I' has a down-turned hook I³ adapted for engagement with a link member L pivotally connected at L' to the trigger F and extending through a slot J⁵ in the rear portion on the frame J. The member L is preferably formed of an inverted U-shaped cross section and near its rear end is apertured to receive the hook I³ and to form a shoulder L² for engaging the same. There is also a curved portion L³ beyond the aperture which when the trigger is pulled rearward will engage a cam J⁶ at the rear end of the slot J⁵ so as to disengage the shoulder L² from the hook I³. Thus, the link L in connection with the cam J⁶ performs the function of a seer, as well as a means for retracting the plunger I' and piston I against the tension of the spring K. Consequently, when the trigger F is pulled it first will move the piston I rearward within the cylinder G, thereby compressing the spring K and at the end of this rearward movement the hook I³ is disengaged from the link L, permitting forward movement of the piston under actuation of the spring. Near the completion of this forward movement a forward extension I⁴ of the shank I' will strike against the disk closure H positively unseating the same, which will be followed by a loud report due to the sudden escape of compressed air.

The trigger F is fulcrumed on a pin F³ and normally bears against a struck-out ear J⁷ on the guide member J. A spring F' about the pivot L' and with end portions bearing against the link L and trigger F, serves to hold this trigger in its normal position and to return the same after being pulled backward. The furcations F² of the bifurcated upper end of the trigger F embrace the guide J, as well as the shank D, the pivot E'

for the pawl E being located above said shank. An ear E² on the pawl E engaging the upper end of the trigger and yieldably held thereagainst by a spring E³ serves to hold the pawl E out of engagement with the ratchet teeth D² when the trigger is in normal position. However, when the trigger is pulled rearward the pawl will be depressed to engage one of the ratchet teeth and to thereby move the shank D and piston C forward so as to discharge water from the cylinder B through the aperture B². Upon the return movement of the trigger the pawl E will be drawn rearward into engagement with another one of the ratchet teeth, the spring E³ yielding to permit such movement.

With the construction as described, to load the cylinder B with liquid the apertured end B' is immersed in a container for the liquid and the plunger D drawn rearward by the loop D' to the limit of its movement which is determined by a stop D³ engaging the rear wall of the casing. The gun is then ready for use and each time the trigger F is pulled rearward the piston C will move forward ejecting a measured quantity of liquid from the cylinder through the aperture B². At the same time, the movement of the trigger will, through the link L, draw the hook I³ and piston I rearward, compressing the spring

K and finally releasing the hook to produce the report. Thus, substantially simultaneously with the discharge of the liquid projectile a loud report is sounded, thereby closely simulating the action of a firing gun.

What I claim as my invention is:

A toy gun comprising a casing having a double barreled portion, a liquid holding cylinder located in the upper barrel, an air cylinder located in the lower barrel, a plunger in said liquid cylinder having a shank extending through the rear end of the casing and provided with a series of teeth in the portion within the casing, a plunger in the air cylinder having a rearwardly extending shank adjacent to the shank of the aforesaid plunger, a trigger having a bifurcated portion embracing both of said plunger shanks and a pawl connected to its upper end for cooperating with said ratchet teeth to advance the liquid cylinder plunger step by step, a link connected to said trigger and engaging said air cylinder plunger shank to retract the same simultaneously with the advancement of said liquid cylinder plunger shank, and means cooperating with said air cylinder its plunger and plunger shank for producing a report.

CHARLES F. LEFEVER.
